United States Patent Office.

OBADIAH JONES, OF SOUTH ENGLEWOOD, NEW JERSEY.

Letters Patent No. 68,513, dated September 3, 1867.

IMPROVED LEATHER-BACKED HORSE-BRUSH.

The Schedule referred to in these Letters Patent and making part of the same.

TO ALL WHOM IT MAY CONCERN:

Be it known that I, OBADIAH JONES, of South Englewood, (Jones Road,) in the county of Bergen, and State of New Jersey, have invented a new and useful improvement in Leather-Backed Horse-Brushes; and I do hereby declare that the following is a full, clear, and exact description thereof, which will enable others skilled in the art to make and use the same, reference being had to the accompanying drawing, forming part of this specification, in which—

Figure 1 is a longitudinal sectional view of my improved horse-brush, showing it in process of construction.

Figure 2 is a longitudinal sectional view of the same when completed.

Figure 3 is a transverse sectional view of the same.

Similar letters of reference indicate like parts.

This invention relates to a new kind of horse-brushes, and to the manner of making the same, and consists in making a leather-backed, round-faced horse-brush, and in inserting a core, which is made of one or more pieces of leather or other suitable pliable material, between the back and face-leather coverings, whereby the desired shape is given to the formerly straight face-cover, in which the bristles have before been secured.

The different pieces of leather are glued together, and the face and back pieces are firmly connected by means of rivets. In the same manner the leather handle is secured to the back piece.

I am aware that leather-backed brushes have already been made, also that round-faced brushes are already in use, but the two combined have never been made, although such a brush is more convenient than those now used. The round-faced horse-brush is generally considered to be superior to the flat-faced brush, as it can be more conveniently applied, and if the back of such a brush is made elastic and pliable, its value and efficiency will be greatly increased.

A represents a piece of leather cut in the proper form, according to the shape of the brush. It may, if desired, be glued to another piece, *a*, of similar form, both of which will then constitute the back of the brush. B is the face-plate, made also of leather of proper length and width. The bristles C are secured in the plate B in any suitable manner. D is a convex block or core, composed of one or more pieces of leather, which are glued together. The upper surface of this core is flat, and is glued to the under side of the back A. The lower side is rounded, and gives the required shape to the face B when the same is laid around it. The outer edges of the back and face-plates are riveted together by means of pins *b b*, as is clearly shown in fig. 2. E is the leather handle, the ends of which are also secured to the back by means of rivets *c*, which also pass through the face-plate, as is clearly shown in fig. 3. The bristles are secured to the face B while the same is flat, and are attached to the same by means of wires or otherwise. The back is secured to a board, and the core glued to it, as shown in fig. 1, and then the flat face is applied and bent on the core, and glued to the same, whereby the face will be rounded. When dry the brush is removed from the board, the edges are trimmed and riveted, and then finally the handle is secured. If desired, the bristles may be attached to the face after the same has been secured to the core, and while it is already rounded. The brush is then also secured to a board, with the cover glued, and when dry finished as before described.

What I claim as new, and desire to secure by Letters Patent, is—

The round-faced leather-backed horse-brush, constructed as described, consisting of the strips of leather D, of unequal length, glued together and to the back A, composed of strips of leather *a*, the bristle-plate B, secured to the smaller pieces of the core D, bent around said core and secured to the back A, as herein set forth for the purpose specified.

OBADIAH JONES.
